CLAIM

The ornamental design for a doll, as shown and described.

DESCRIPTION

FIG. 1 is a front perspective view of a doll;
FIG. 2 is a rear perspective view thereof;
FIG. 3 is a front elevation view thereof;
FIG. 4 is a left side elevational view thereof;
FIG. 5 is a right side elevational view thereof;
FIG. 6 is a rear elevation view thereof;
FIG. 7 is a top plan view thereof;
FIG. 8 is a bottom plan view thereof; and,
FIG. 9 is an alternate front elevation view thereof, with the
face shield shown in an alternate position revealing the face
of the doll.
The broken lines shown in the drawings depict portions of
the article which form no part of the claimed design.
